UNITED STATES PATENT OFFICE.

ROBERT CLARENCE DUNBAR, OF OTTAWA, CANADA.

LOOSE-LEAF BINDER.

1,068,115.

Specification of Letters Patent.

Patented July 22, 1913.

Application filed October 10, 1912. Serial No. 724,913.

To all whom it may concern:

Be it known that I, ROBERT CLARENCE DUNBAR, a subject of the King of Great Britain, and resident of the city of Ottawa, 5 Canada, have invented certain new and useful Improvements in Loose-Leaf Binders, of which the following is a specification.

The invention relates to improvements in loose leaf binders, as described in the present specification, and illustrated in the accompanying drawings that form part of the same.

The invention consists essentially of a flanged backplate formed of an integral 15 piece of sheet metal, and having a flanged tiltable tongue portion carrying filing posts, and adapted to interlock with the remaining portion of the back-plate.

The objects of the invention are to devise 20 a binder for filing letters or other loose leaf documents and papers, which shall be of light and durable construction and most inexpensive with the fewest number of parts possible.

25 In the drawings, Figure 1 is a perspective view of the binder with several leaves held therein. Fig. 2 is an elevation view of the binder from the inside. Fig. 3 is a mid-cross sectional view of the binder when 30 opened. Fig. 4 is a mid-cross sectional view of the binder when closed.

Like numerals of reference indicate corresponding parts in each figure.

Referring to the drawings, 1 is the backplate having the flange 2 extending along 35 one side thereof, and the tongue portion 3 formed therefrom, and leaving the side strips 4.

40 5 is a flange formed along the edge of the tongue 3, and corresponding with the flange 2.

6 are orifices through the flange 2.

7 is a ridge formed of the flange 2 by depressing the same toward the back of the 45 binder, the edge of said ridge being set in from the edge of the flange 2 by approximately the thickness of the metal used.

10 are filing posts projecting upwardly 50 from the flange 5 opposite the orifices 6 of the flange 2.

It must be understood that the back plate 55 with the tongue and the flanges as herein described are all formed from the one sheet of metal, having sufficient spring to normally take the position shown in Fig. 3, that is, with the tongue inclined inwardly at

the upper end, and the flange thereof turned therewith to tilt the filing posts with the upper ends thereof clear of the flange 2, whereby papers after being suitably perforated may be readily filed thereon.

To close the binder it is only necessary to press the tops of the side strips 4 with the flange 2 inwardly until the depressed portion 7 forming the ridge on the flange 2 60 passes over the tongue 3, and springs downwardly with the edge thereof outside the ridge resting evenly on the top of the tongue 2, the said ridge meeting the inner side of the tongue 3, thus securely locking the 65 binder. As the ridge 7 passes over the tongue 3 the flange 2 springs upwardly, clearing the tops of the posts 10, and when the flange 2 springs downwardly into position upon the top of the tongue 3, the filing 70 posts 10 enter the orifices 6, wherein they are firmly held.

To open the binder for the purpose of removing sheets therefrom, or filing additional sheets thereon, it is only necessary to 75 bear upwardly on the center of the flange 2, until the ridge 7 clears the top of the tongue 3. The same action also disengages the filing posts 10 from the orifices 6, and the flange 2 is carried outwardly over the top 80 of the tongue 3 by the spring of the metal in the side strips 4, leaving the filing posts 10 freely accessible. It is not possible to open the binder except by this positive upward pressure on the center of the flange 2, 85 and as such a pressure could not be applied by any accidental means, there is no danger of the binder being opened by a fall or other accident.

The binder as shown and described is of 90 the simplest possible construction, and is readily formed from the one piece of sheet metal at a minimum cost, and when completed is most attractive in appearance, and if desired may be covered on the outer surface with material such as cloth, leather or 95 paper as customary with book-back bindings. It will be observed that, while the binder opens freely and locks securely, no rivets, hinges, springs or catches are used 100 in its construction. It is of uniform strength throughout, and the only friction occurs at the point 7, so that it is practically 105 free from wear and indestructible.

What I claim as my invention is;

110
1. A loose leaf binder comprising a back plate formed of an integral piece of sheet

metal having a flanged tiltable tongue portion and a filing post secured to said tongue and tiltable therewith.

2. A loose leaf binder comprising a back plate having side flanges and a tongue formed therefrom and arranged to spring with one of said flanges to a tilted position, binding posts secured to said tiltable flange and means for retaining said tiltable tongue and binding posts in squared position in said back plate.

3. A loose leaf binder comprising a back plate having flanges formed along the sides thereof and a tongue extending laterally across the back from one of said flanges and

leaving lateral end strips adapted to spring said tongue and the flange therewith to a tilted position, binding posts secured at one end thereof to said tiltable flange, orifices arranged in the other of said flanges, and adapted to receive the tiltable ends of said binding posts and a depression formed from one of said flanges and interlocking with the tiltable end of said tongue. 20

Signed at Ottawa this sixth day of September, 1912.

ROBERT CLARENCE DUNBAR.
